HAIRCUTTING MACHINE WITH ADJUSTABLE CUT REGULATOR

Ferdinand Majer, Zurich, Switzerland, assignor
to Hans Majer, Zurich, SwitzerlandApplication March 26, 1945, Serial No. 584,883
In Switzerland April 18, 1944

4 Claims. (Cl. 30—201)

1

This invention relates to an electrically driven hair cutting machine with adjustable cut regulator in which, according to the invention, the movable cutting comb is displaceable in the longitudinal direction of the comb teeth, thereby to permit of adjusting the machine to various lengths in which the hair is to be cut.

In order to render the above-mentioned adjustment effective over a relatively great range the stationary cutting comb is advantageously provided on two oppositely disposed portions with comb teeth which have different tooth lengths and can be turned relative to the movable comb for the purpose of providing for its comb teeth on one or the other portion to cooperate with the movable cutting comb.

An exemplification of the hair cutting machine according to the present invention is illustrated in the accompanying drawings of which

Fig. 1 shows a side elevation of the cutting head;

Fig. 2 shows an end elevation of the machine;

Fig. 3 is a view of the cutting head similar to Fig. 1 with the stationary cutting comb omitted;

Fig. 4 shows a section on the line IV—IV in Fig. 3;

Fig. 5 shows the driving arrangement for the movable cutting comb, and

Fig. 6 shows a section on the line VI—VI in Fig. 1.

Referring to the drawings the numeral 1 designates the casing and 2 denotes the cutting head of the machine. Driving motion is imparted from a motor (not shown) to the movable cutting comb 3 via a shaft 4, a worm 5, a worm wheel 6, levers 7 and 8 and a rocking lever 9 one end of which engages with a slide block 10 in a recess of the latter. A stationary cutting comb 11 is provided on two opposite end portions with comb teeth 12 and 13.

This stationary cutting comb 11 can be turned about a bolt 14 so that, dependent upon choice, the comb teeth 12 and 13 can respectively be moved into position for cooperation with the movable comb 3. The bolt 14 is screwed into a plate 15 which is provided with a recess 16 (Fig. 3) into which projects one end 17 of a two-armed lever 18 whereas the other pin like end 19 of this lever 18 interengages with the forked end 20 of a hand operated lever 22 which pivots on a fulcrum 21.

By turning the hand operated lever 22 the stationary cutting comb 11 is shifted in the longitudinal direction of the comb teeth, thereby to adjust the length in which the hair is to be cut,

which depends upon the stretch *a* (Fig. 4) for which the end of the base of the teeth of the stationary comb projects beyond the end of the tooth base of the movable comb, for the reason that the distance *b* of the tooth surface bearing on the portion of the scalp where the cutting occurs to the place of actual cutting is accordingly varied.

The stationary comb 11 is guided in a lid 24 which is pivoted to the casing 1 at 23 and the side walls 25 of which overlap the sides of the comb 11. By swinging the lid 24 upwardly the stationary cutting comb 11 is left free so as to allow of being rotated through an angular range of 180° about the bolt 14 for cooperation of its comb teeth 12 or 13, as the case may be, with the teeth of the movable comb 3. The lengths of the comb teeth 12 and 13 differ from each other so that by varying the tooth length and readjusting the stationary comb considerable variation of the length in which the hair is to be cut ensues.

The actuating lever 8 is provided with a longitudinal slot 8' and a cross slot 8''. By shifting the connecting means between the levers 7 and 8 longitudinally of the slot 8' the length of traverse of the movable comb can be varied and by shifting the connecting means between the lever 6 and the rocking lever 9 along the cross slot 8'' the place of traversing of the movable comb can be shifted to the left or right hand side. By this means the most desirable cutting effect can be obtained.

I claim:

1. In an electrically driven hair cutting machine inclosed in a casing, a pivotal lid having side walls arranged on said casing, a cutting comb stationarily arranged in the machine between said side walls on said lid, a drivable cutting comb arranged for reciprocation relative to said stationary cutting comb, oblong comb teeth on each of said two cutting combs for cooperation with each other for effecting the cutting of the hair, and means for adjusting said stationary cutting comb in the longitudinal direction of said oblong comb teeth relative to said movable cutting comb for setting said machine for cutting the hair in various lengths.

2. In an electrically driven hair cutting machine inclosed in a casing, a pivotal lid having side walls arranged on said casing, a cutting comb stationarily arranged in the machine between said side walls on said lid, a drivable cutting comb arranged for reciprocation relative to said stationary cutting comb, oblong comb teeth

fixed to said drivable cutting comb, two sets of oblong comb teeth of different tooth length provided on said stationary cutting comb, means for selectively turning either of said sets of cutting teeth on said stationary cutting comb into position for cooperation with said comb teeth on said drivable cutting comb, a hand operated control lever pivoted to said casing, and a pivotal lever mounted in said machine and operatively connected at its ends with said control lever and said stationary cutting comb respectively for adjusting said stationary comb in the longitudinal direction of said oblong comb teeth relative to said movable cutting comb for setting said machine for cutting the hair in various lengths by means of the respective said sets by correspondingly operating said control lever.

3. In an electrically driven hair cutting machine, a cutting comb stationarily arranged in the machine, a cutting comb arranged for reciprocation relative to said stationary cutting comb, a drive for actuating said reciprocatory cutting comb, setting means provided in said drive for adjusting said reciprocatory cutting comb for varying the length of traverse as well as for changing the place of traversing of said reciprocatory cutting comb relative to said stationary cutting comb, and means for adjusting said stationary cutting comb in the longitudinal direction of said oblong comb teeth relative to said movable cutting comb for setting said machine for cutting the hair in various lengths.

4. In an electrically driven hair cutting ma-

chine, a cutting comb stationarily arranged in the machine, a cutting comb arranged for reciprocation relative to said stationary cutting comb, a drive for actuating said reciprocatory cutting comb, an actuating lever carrying a longitudinal and a transverse slot provided in said drive, said transverse slot for guiding a settable connecting means for adjusting said reciprocatory cutting comb for varying the length of traverse as well as for changing the place of traversing of said reciprocatory cutting comb relative to said stationary cutting comb, connecting means adjustably received by said actuating lever by means of said longitudinal slot from the part of said drive adjoining said actuating lever for setting said part, and means for adjusting said stationary cutting comb in the longitudinal direction of said oblong comb teeth relative to said movable cutting comb for setting said machine for cutting the hair in various lengths.
